[54] METHOD FOR MAKING ROCK BITS

[52] U.S. Cl. ..... 219/121 EM; 175/375;
76/108 A

[75] Inventor: **Richard E. Goetz**, Huntington Beach,
Calif.

[57] ABSTRACT

[73] Assignee: **Smith International, Inc.**, Irvine,
Calif.

A method of making a rock bit which is a welded assembly of legs each carrying a rotatable cutter. Electro-chemical grinding is used for finish machining of mating surfaces of heat-treated bit legs, and the legs are secured together by electron-beam welding along the mating surfaces.
